UNITED STATES PATENT OFFICE

ROMEO O. CARUSO, OF READING, PENNSYLVANIA

HAIR-WAVING DEVICE

Application filed April 6, 1929. Serial No. 352,964.

This invention relates to improvements in hair waving devices and it pertains more particularly to that class of devices which comprise a waving tube and a curling pin, by means of which a permanent wave may be produced.

The invention contemplates a magnetic induction heater and a perforated curling pin, the interior of which pin is hollow and provided with an absorbent member for providing moisture or liquid treatment to the hair and a pair of hair clips to hold the hair in position when wound, which combination will prevent burning or scorching of the hair and also permit a very noticeable saving of time in preparing the curlers and heaters preparatory to the waving.

The invention is more fully described in the following specification and clearly illustrated in the accompanying drawing, in which:—

Figure 1 is an outside view of the device in substantially full size.

Figure 2 is a longitudinal central sectional view of the device, somewhat enlarged, but showing the perforated curling pin, in full.

Figure 3 is a sectional view through 3—3 of Fig. 2.

Figure 4 is a sectional view through 4—4 of Fig. 2.

Figure 5 is a separate view of the curling pin, with the clamps in open position, and

Figure 6 is a sectional view, longitudinally of the curling pin, appreciably enlarged.

The numeral 1 designates a stem, the one end of which is split, as at 2, to provide means for engaging the ends of the hair. This stem is encased in a perforated, tube-like member 3, and interposed between the stem and this tube I provide a suitable absorbent material 4. To the outside of the tube 3, I secure, pivotally, and at opposed points, a pair of hair clamps 5, intended to and capable of holding the wound hair on the curling pin. The one end of the pin is provided with a suitable handle portion 7.

The numeral 10 designates the heater, provided with an induction coil 11, as indicated in Figure 2, and made up of three tubular sections, 12, 13 and 14, located one within the other and having air spaces between their

walls, 16, to prevent overheating and to insure comfortable handling.

The induction coil is entered through the opening 20 in the outer tubular section, and is wound in the space between the innermost section and the one next enclosing it, as shown at 22, in Figure 2.

It will be noted that with this construction, the curling pin is first immersed in the liquid provided for the treatment, and the absorbent material around the stem insures the proper moisture reaching the hair, through the perforations in the curling pin, without coming into direct contact with the hair itself.

The magnetic induction heater, in the form shown, will insure proper application of heat without the hair coming into direct contact with a highly heated surface, and the spacing of the heater sections insures sufficient heat insulation to provide assured comfort in handling it.

Having thus fully described my invention, what I claim and desire to secure by Letters Patent is:—

1. A hair waving device comprising in combination a hollow, perforated curling pin with a liquid absorbent material located therein, and a pair of hair securing clamps pivotally attached to the outer surface thereof and a magnetic induction heater adapted to receive said curling pin, said heater comprising a plurality of tubular casing members located one within the other and having air spaces between them and an induction coil wound around the outer surface of the innermost tubular members.

2. In a hair waving device comprising in combination, a magnetic induction heater comprising a plurality of tubular members located one within the others and having air spaces between them, an induction coil in one of said spaces, and a curling pin comprising a stem, and a hollow casing surrounding it and provided with a series of perforations and having a pair of hair clamps pivotally secured to opposed points on its outer surface.

3. A hair waving pin comprising a stem, a perforated casing surrounding the stem, a body of absorbent material interposed be-

tween the stem and the casing, means on the end of the stem for engaging the ends of the hair to be waved and a pair of spring hair clamps, pivotally secured at opposed points on the outer surface of the casing.

4. A magnetic induction heater for hair waving curling pins comprising a plurality of tubular members, located one within the other and having air spaces between the outer surface of one and the inner surface of the other, and a magnetic induction coil wound in one of said spaces whereby the interior of the heater is provided with sufficient heat to wave the hair on a waving pin located therein.

15 In testimony whereof I affix my signature.

ROMEO O. CARUSO.
